Bellevue, Nebr. 68005

Filed May 6, 1974, Ser. No. 467,068

Term of patent 14 years

Int. Cl. D26—05

U.S. Cl. D48—4 A

FIG. 1 is a front elevational view of a decorative form for holding lights showing my new design; and

FIG. 2 is a right side elevational view thereof.

The rear, top and left sides of the L-shaped member are flat and plain. The rear of the scroll member is also flat and plain.

The circles in FIG. 1 indicate light sockets which in depth extend halfway through the thickness of the form.

I claim:

The ornamental design for a decorative form for holding lights, substantially as shown and described.
